William A. Ringler, Wayne, Pa., assignor to The
Gardner Board and Carton Co., Middletown,
Ohio, a corporation of Ohio

Application March 9, 1950, Serial No. 8,428

Term of patent 14 years

(Cl. D58—26)

To all whom it may concern:

Be it known that I, William A. Ringler, a citizen of the United States of America, residing at Wayne, in the county of Delaware and State of Pennsylvania, have invented a new, original, and ornamental Design for a Collapsible Bottle Carrier, of which the following is a specification, reference being had to the accompanying drawing, forming a part hereof.

Figure 1 is a side elevational view of a collapsible bottle carrier in erected condition showing my new design.

Figure 2 is an end elevation thereof.

Figure 3 is a top plan view thereof.

Figure 4 is a perspective view thereof taken on a reduced scale.

Figure 5 is a perspective view of the carrier in partially collapsed condition.

The characteristic feature of my design resides in the handle yoke members extending along the top edge of the handle and terminating adjacent the end wall portions, the ends of the yoke mem-

bers extending downwardly an appreciable distance below the tops of the said end wall portions, with the extension of the opening, which constitutes the hand hole feature, extending a substantial distance below the central portion of the handle, and lying between the respective ends of the handle yoke members.

I claim:

The ornamental design for a collapsible bottle carrier, substantially as shown and described.

WILLIAM A. RINGLER.
